UNITED STATES PATENT OFFICE.

LEON P. LOWE, OF SAN FRANCISCO, CALIFORNIA.

PROCESS OF MAKING GAS.

No. 882,764.

Specification of Letters Patent. Patented March 24, 1908.

Application filed August 23, 1905. Serial No. 275,336.

To all whom it may concern:

Be it known that I, LEON P. LOWE, a citizen of the United States, residing at San Francisco, in the county of San Francisco and State of California, have invented certain new and useful Improvements in Processes of Making Gas, of which the following is a specification.

This invention relates to a process of 10 manufacturing gas, the object of the invention being to provide a process by which gas can be manufactured with greater economy than heretofore.

In the accompanying drawing, Figure 1 is 15 a side elevation of an apparatus used in carrying out the process, the generator being shown in vertical section; Fig. 2 is a plan view thereof.

Referring to the drawing, 1 represents the 20 casing of a generating chamber, the main portion of which is divided by arches 2 into three compartments 3, 4, 5, each compartment supporting refractory material 6. The uppermost compartment 5 connects with a 25 flue 7, closed by a valve 8 and leading to the mouth of a stack 9. The lowest compartment 3 connects with a passage 10 formed by a partition 11 and a protective wall 12, the latter forming the back of a coking and combustion chamber 13, said passage connecting 30 with said chamber over the top of said wall. Said coking and combustion chamber 13 is provided with a door 27 for feeding the material to be coked and with the lower door 35 28, shown in dotted lines for removing said chamber. Into the top of said coking and combustion chamber 13 discharges an oil pipe 14, the oil being atomized by steam through a pipe 15. Air for 40 combustion is also supplied by a pipe 16 controlled by a valve 17.

Into the top of the uppermost compartment 5 discharges a steam pipe 18 and into the top of the intermediate compartment 4 45 discharges an oil pipe 19, the oil being atomized by steam through a pipe 20. From the top of the lowest compartment 3 leads a gas outlet pipe 21, which leads to a washer 24 from which the gas passes by a seal 25 to the 50 usual scrubbers, purifiers, etc.

The coking chamber 13 having been charged with the material to be coked, the first step of the process is the heating stage, in which oil at the burner 14 is burned by 55 means of air admitted through the pipe 16. This combustion is continued a considerable

time, the products of combustion impinging against the protective wall 12, passing down the passage 10 and then up through the several chambers 3, 4, 5, in succession heating the refractory material 6 therein and escaping by the flue 7. The refractory material having been sufficiently heated for the purpose of gas making, the valves 8 and 17 are closed, and the gas making stage commences.

In order to understand the nature of this invention, it is to be remembered that when oil is passed over sufficiently highly heated refractory material it is broken down and 70 converted into solid carbon in the form of lamp black and into gaseous products of varying luminosity, the degree of luminosity of the gases so produced varying with the heat applied thereto. If the heat be sufficiently great, the resulting gases may be 75 principally non-luminous gases such as hydrogen and marsh gas. As the temperature of the refractory material falls the oil is not so highly decomposed, but gases of greater 80 chemical complexity and greater luminosity are produced. That is to say, in the process of gas making, by which oil is partly broken down into solid carbonaceous substances the first gases which are produced when the gas 85 making stage commences, are of very low candle power, which increases as the gas making stage progresses. All these gases are, however, commingled in the gas holder so that a substantially uniform gas results. 90 However, by my present process the gas produced is substantially uniform as it is produced. The principal advantage of this is that gas is produced more economically and with less waste of oil converted into solid 95 carbon than with such heretofore existing processes. Therefore, after the preliminary stage of heating has been carried on to a sufficient extent, the air blast is shut off by the valve 17 and the valve 8 leading to stack 9 is 100 closed.

Steam is introduced through the pipe 18, and oil is introduced through the pipes 19 and 14. The steam introduced through the pipe 18 is superheated by the refractory material in chamber 5 and mixes with the oil introduced through the pipe 19 combining with that portion of the oil broken down into solid carbon to form hydrogen and carbonic acid gases, a portion of the oil forming a rich fixed oil gas. At the same time the oil passes through the pipe 14, together with a certain 105 110

amount of steam admitted through pipe 15, and the gases distilled from the tarry residue, or other coking material charged into the chamber 13 are passed upwards through the 5 highly heated chamber 3, the effect being to break down the oil largely into solid carbonaceous form and non-luminous gases. These gases intermingle in the top of the chamber 3 with the fixed gases of comparatively high 10 candle power obtained from the steam and oil passing downward, and the resulting gas is drawn off by the pipe 21, being a gas of substantially the required degree of luminosity. As the temperature of the refractory 15 material in chamber 3 fails, less solid carbon is formed and the candle power of the gas increases and the amount of oil passed through the pipe 19 may be gradually diminished in order to prevent too rich a gas being formed. 20 By this means the luminosity of the gas produced is maintained substantially uniform. The coke can be withdrawn from time to time by the door 28.

Inferior modifications of my invention consist in omitting the introduction of steam, either in the updraft, or in the downdraft, or in the passage of oil through the generator.

I claim:

1. The process of manufacturing gas 25 which consists in passing products of combustion of oil and air entirely through a chamber containing loosely piled refractory material, to highly heat said refractory mate-

rial then excluding the air and passing the oil partly through the chamber and the refractory material therein in the same direction as in the heating stage, and simultaneously passing steam and oil through the chamber and the refractory material in the opposite direction and drawing off the generated gases together, substantially as described. 35 40

2. The process of manufacturing gas which consists in passing products of combustion of oil and air entirely through a 45 chamber containing loosely piled refractory material, to highly heat said refractory material then excluding the air and passing the oil partly through the chamber and the refractory material therein in the same direction 50 as in the heating stage, and simultaneously passing in the opposite direction steam through part of the refractory material to superheat the same, and oil commingled with the steam so superheated through refractory 55 material in the chamber and drawing off the generated gases together, substantially as described.

In witness whereof I have hereunto set my hand in the presence of two subscribing witnesses. 60
